ELECTRIC ARC FURNACE AND CRANE STRUCTURE

Application filed June 18, 1930. Serial No. 461,947.

This invention relates to electric arc furnaces and especially to the electrode-carrying mechanism or crane structure of such furnaces. More particularly the invention aims 5 to provide a mast of improved construction forming a part of the crane structure, and an improved means for mounting the masts upon the furnace.

Electric furnaces of the so-called arc type 10 comprise generally a heating chamber into which a charge of metal scrap or ore is introduced and a plurality of electrodes connected with a source of electrical energy. By establishing arcs across the space separating 15 the electrodes from the charge a circuit is completed through the charge which melts in consequence of the terrific heat generated. The furnace is customarily arranged for tipping movement to pour off the molten metal 20 and the slag. In such type of furnace it is usual to mount the electrodes for vertical movement to permit maintaining the most effective arcing interval between the electrodes and the charge within the heating 25 chamber, which interval must necessarily vary in accordance with changes in the temperature of the charge, the current maintained, and also to compensate for the gradual consumption of the electrodes at their 30 points during operation of the furnace. For this purpose a crane is usually provided for each electrode which consists essentially of an electrode holder mounted upon a carriage which is adapted to be raised and lowered 35 along a mast or standard extending vertically above the furnace. One object of the present invention is to provide an improved mounting for the electrode mast by which the weight of the mast is carried entirely by the 40 base of the furnace. Another object of the invention is to provide a mast assembly permitting a plurality of masts to be removably attached to the furnace as a unit.

This object is accomplished by providing 45 a combination of several masts rigidly mounted together to form a mast structure which may be removed bodily for shipment and which may be attached to the furnace in such a manner as to rest on a suitable 50 supporting member of the furnace proper.

This combination mast structure comprises one or more structural members, such as steel plates, at its lower end to which the masts are individually welded, and another member at or near the top of the masts, whereby the masts and structural members form a rigidly connected frame which can be bolted or otherwise attached to the supports on the furnace shell. 55

Various types of masts have been used in the past, one of which is disclosed in Patent No. 1,751,913, of Albert E. Greene, issued March 25, 1930, consisting of a structural I-beam, of which the exterior surfaces of the flanges provide tracks for a set of rollers carried by the electrode carriage. While such type of mast is satisfactory in those cases where there is little or no tendency to twisting of the mast, as where the mast is so mounted upon the tiltable furnace as to be 60 swung in a plane parallel to its web, under conditions where the mast is rigidly affixed to and at one side of the furnace and arranged to swing with the furnace during its 65 pouring operation in a direction transversely 70 of the plane of the web there results torsional stresses upon the mast which tend, if not to fracture, at least to cause temporary or permanent deformation of the flanges permitting 75 the electrode to shift laterally. An 80 important object of the present invention is to provide a mast of such rigidity of construction as to withstand these torsional stresses. More particularly this end is attained by providing a mast of such cross-section 85 as to insure the greatest strength at the points most susceptible to fracture or deformation.

The above features and others will now be described with reference to the annexed 90 drawings, in which:

Fig. 1 is a front elevation of an electric arc furnace mounted for tipping movement, showing the manner by which the mast structure and electrode-carrying mechanism, are 95 connected therewith as contemplated by the present invention.

Fig. 2 is a plan view of the furnace shown in Fig. 1, the hoists being omitted;

Fig. 3 is a sectional view of one improved 100

form of mast composed of two channel irons.

Fig. 4 is a sectional view of a modified form of mast made up of four metal plates rigidly connected together.

Fig. 5 is a sectional view of still another form of mast utilizing an I-beam.

In Fig. 1 of the drawing is shown an arc furnace of a conventional type having an upright, generally cylindrical shell 1 forming the melting chamber into which the scrap material or ore is charged, the furnace being mounted upon a pair of rockers 2 to permit tilting in one direction to discharge its molten contents through the pouring opening 4 and 10 tilting in the opposite direction to allow skimming or pouring off the slag through the charging door 5. For rocking the furnace about its axis $a-a$ there is provided a piston 6 pivotally connected at one end to the 15 furnace at one side of its axis and having its other end connected to a plunger working within a hydraulic cylinder 7. A plurality of electrodes 8, in this case numbering three, are supported in a normally vertical position 20 above the furnace shell 1 and extend through its top into the heating chamber where the 25 charge of metal scrap is contained. The upper end of each electrode is connected to a source of electric current in a manner well 30 known in the art.

The electrodes 8 are each arranged for vertical movement by means of a crane consisting generally of an electrode carrying arm 17 mounted upon a carriage 22, a vertically extending mast 9 along which the carriage is adapted to travel, and a drum 18 for raising and lowering the carriage. The cranes are constructed as follows: At one side of the cylindrical furnace shell 1 and aligned at 35 right angles to the transverse axis $a-a$ of the furnace are a series of vertically extending electrode masts 9 their lower ends being welded to a lower plate 10 which in turn is removably bolted upon a platform 10' carried by brackets 11 rigidly fastened to and supported by the furnace base and rockers 2. These masts are maintained rigid and 40 in parallelism with each other by means of a channel iron 12 to which the masts are welded and which acts to tie together their upper 45 ends, and also by means of an intermediate plate 13 also bolted to a flange 1' extending laterally from the furnace at its top. In the intermediate plate 13 holes are preferably 50 cut to receive the masts, the plate and masts then being welded. These holes are cut at the proper position and angle so that the axes of the electrode arms pass approximately 55 through the desired positions of the electrode centers and axes. The mast head plate or channel member 12, as shown in the drawing, may also have holes formed in it corresponding to those in the intermediate plate 13, the masts being welded to this plate.

It will be seen that by this construction the

three members to which the masts are welded, namely the bottom plate 10, the intermediate plate 13, and the top member 12 unite the masts as a unitary structure which possesses sufficient rigidity to withstand the stresses 70 resulting from tipping the furnace, and which is also capable of being quickly bolted thereto. The weight of the mast structure being supported chiefly on the rockers 2 which are mounted below the shell, the shell 75 in consequence is relieved of the weight of this structure, which avoids the occurrence of dangerous stresses which might rupture the shell when weakened by the high temperatures developed during the operation of 80 the furnace.

Arranged to travel longitudinally upon each mast is an arm 17 extending horizontally to a position over the furnace and supporting one of the electrodes 8. This arm is 85 mounted upon the travelling carriage 22 having a plurality of rollers 14 positioned to engage opposite flat faces of the mast 9 which in customary practice heretofore has consisted of either a structural I-beam or a cylindrical post provided with a feather. The rollers 14 are rotatably mounted upon shafts 15 extending between spaced side plates 16 forming a part of a clamp for gripping the electrode supporting arm 17, the arrangement being such that the mast is surrounded on its four sides by the rollers 14 and the two side plates 16. The carriage is arranged to be raised and lowered longitudinally of the mast by means of a drum hoist 18 driven by a worm gear for winding up and playing out a cable 19 which is trained over a mast head sheave 20, suitably journaled within bearings 21 carried upon channel iron 12, and fastened at its end to the arm 17. The drum hoist is supported upon a plate carried by brackets 18' removably attached to the masts 9 and extending in a direction away from the shell 1. The sheave 20 is preferably of large diameter to permit the cable to move without interference from the mast frame but it is understood that the sheave center may be so positioned as to permit one cable to pass down through the mast if desired. The approximate alignment of 100 the backs of the masts 9 allows the gear mounting brackets 18' to be removably attached to the rear of the masts away from the shell 1. This affords a very simple mounting for the worm-gear drum hoists 18 on top of the plate carried by these brackets and permits, if desired, placing individual motors beneath the plate—one for 105 each hoist.

By referring to Fig. 2 it will be apparent that as the furnace is tipped on its rockers 2 there will be a tendency for the electrode carrying arm 17 to swing under gravitational influence in the direction indicated by the arrow in Fig. 2 into a plane perpendic-

125

130

ular to the axis $a-a$. This twisting moment due to the relatively great mass composing the electrode-carrying arm and electrode at the end of the arm and due also to the fact 5 that the mast at the point intermediate its length at which the stress is applied is of necessity free from adjacent support, frequently approaches a dangerous limit. Such stress as is transmitted to the mast 9 through 10 the rollers 14, it will be seen, must be resisted in greater part by the marginal portions or corners of the mast. Consequently these portions of the mast must be made especially rigid to resist any tendency to deform or 15 fracture under such stresses.

This condition is met in the construction shown in Fig. 3 in which the mast is made of two structural members, preferably channel irons, arranged in opposed relation with 20 their flanges extended toward each other and rigidly united, as by welding, along their surfaces of contact. This results in a mast of rectangular cross-section providing track members 31 (which may be smoothed by 25 machining so as to offer negligible frictional resistance to the rollers 14) and connecting walls 32 which unite with the track members at their two longitudinal edges. Tendency of the arm to shift to one side by reason of 30 flexing of the flanges is thus avoided. Furthermore, a mast of such a cross-section most effectively resists longitudinal bending and offers a firm support for the rollers. This type of mast is extremely simple to make 35 while at the same time affording a high degree of strength and rigidity for counter-acting the tortional stresses incident to tilting of the furnace. Instead of welding, the two channel irons may be bolted or otherwise 40 firmly fastened together.

Another form of mast of approximately rectangular cross-section is shown in Fig. 4. In this embodiment of the invention, instead of the union of two channel irons along their 45 edges, the mast is composed of two spaced track plates 41 of cold rolled steel forming the surface along which the rollers travel, these plates being connected by means of two spacing channels 42 united as by welding to 50 the track plates 41 adjacent their edges. This form of mast has all the advantages possessed by the one previously described and in addition provides a double thickness of metal at the edges of the mast. It is not 55 necessary however that the walls 42 should be constituted of channel irons but these walls may comprise flat plates united at their edges to the track plates 41.

Still another modification is shown in Fig. 60 5, in which an I-beam is strengthened by reinforcing plates 51 extending transversely between the flanges and welded adjacent the edges of the flanges 52. This construction effectively prevents fracturing or bending 65 of the flanges under load as described above.

This arrangement does not permit of any adjustment of the position of one mast relative to the others; nor does it permit of any angular shifting of the arm axis for the purpose of swinging the electrode to one side or the other of its normal position. But the construction of the mast is materially simplified and provision is made for lateral adjustment of the electrode by other means on the electrode arm not forming part of the present invention. 70 75

The upper ends of the masts 9 may in certain cases project through openings formed in the channel iron 12 and the sheaves 20 may be mounted in the sides of the masts 9 80 which extend above the channel iron 12.

What I claim is:

1. In an electric arc furnace comprising a shell enclosing a heating chamber and mounted for tilting movement, an electrode extending through the top of the shell into the heating chamber, and an arm arranged to support the electrode in an upright position above the shell, means for permitting vertical movement of the arm, said means consisting of a mast rigidly connected at one side of the shell and a carriage for the arm having rollers arranged to engage opposite faces of the mast, said mast being composed of two spaced track members and two spacing elements each rigidly connected to the track members adjacent the edges of the track members. 85 90 95

2. In an electric arc furnace comprising a shell enclosing a heating chamber and mounted for tilting movement, an electrode extending through the top of the shell into the heating chamber and an arm arranged to support the electrode in an upright position above the shell, means for permitting vertical movement of the arm consisting of a mast rigidly connected at one side of the shell and a carriage for the arm having rollers arranged to engage opposite faces of the mast, said mast being of approximately box formation. 100 105 110

3. In an electric arc furnace comprising a shell enclosing a heating chamber and mounted for tilting movement, an electrode extending through the top of the shell into the heating chamber and an arm arranged to support the electrode in an upright position above the shell, means for permitting vertical movement of the arm consisting of a mast rigidly connected at one side of the shell and a carriage for the arm having rollers arranged to engage opposite faces of the mast, said mast being composed of four plates welded together to provide a mast of approximately rectangular cross-section. 115 120 125

4. In an electric arc furnace comprising a shell enclosing a heating chamber and mounted for tilting movement, an electrode extending through the top of the shell into the heating chamber and an arm arranged to support 130

- the electrode in an upright position above the shell, means for permitting vertical movement of the arm consisting of a mast rigidly connected at one side of the shell and a carriage for the arm having rollers arranged to engage opposite faces of the mast, said mast being composed of two channel irons having their edges extended toward and in abutting relation with each other and welded along their line of junction.
5. In combination with an electric arc furnace comprising a furnace base and a shell, a removable electrode crane structure consisting of a bottom plate, a plurality of masts welded thereto, an intermediate plate to which the masts are welded, a plate joining the masts at their tops, means for supporting the bottom plate on the furnace base and means for attaching the intermediate plate to the shell structure.
10. In combination with an electric arc furnace comprising a furnace base and a shell enclosing a heating chamber, a removable electrode crane structure consisting of a bottom plate, a plurality of masts welded thereto, an intermediate plate to which the masts are welded, a plate joining the masts at their tops, means for supporting the bottom plate on the furnace base, and means for attaching the intermediate plate to the shell structure, said masts being arranged with their outer flanges in approximate alignment.
15. In combination with an electric arc furnace comprising a furnace base and a shell enclosing a heating chamber, a removable electrode crane structure consisting of a bottom plate, a plurality of masts welded thereto, an intermediate plate to which the masts are welded, a plate joining the masts at their tops, means for supporting the bottom plate on the furnace base, and means for attaching the intermediate plate to the shell structure, said masts extending thru openings in the intermediate plate and being welded thereto.
20. In combination with an electric arc furnace comprising a base, shell supported by the base and enclosing a heating chamber, an electrode extending through the top of the shell into the heating chamber, and arms arranged to support a plurality of electrodes in an upright position above the shell, means for permitting vertical movement of the arms consisting of a plurality of masts rigidly connected at one side of the shell, a bottom plate, an intermediate plate to which the masts are welded, a plate joining the masts at their tops, means for supporting the masts on the furnace base, means for attaching the intermediate plate to the shell structure, and a plurality of hoists mounted in a position between the mast supporting means and the intermediate plate.

In testimony whereof I affix my signature.
ALBERT E. GREENE.
